(57) **CLAIM**

The ornamental design for a lid for use with insert for slow cooker, as shown and described.

DESCRIPTION

FIG. 1 is a top front perspective view of a lid for use with insert for slow cooker in accordance with one embodiment of the invention;

FIG. 2 is a front elevation of the lid;

FIG. 3 is a right side elevation of the lid, the left side elevation being a mirror image thereof;

FIG. 4 is a rear elevation of the lid;

FIG. 5 is a top plan view of the lid;

FIG. 6 is a bottom plan view of the lid;

FIG. 7 is a top rear perspective of the lid;

FIG. 8 is a front elevation of a lid in accordance with a second embodiment of the invention;

FIG. 9 is a right side elevation of the lid in accordance with the second embodiment of the invention, the left side elevation being a mirror image thereof;

FIG. 10 is a rear elevation of the lid in accordance with the second embodiment of the invention;

FIG. 11 is a top plan view of the lid in accordance with the second embodiment of the invention; and,

FIG. 12 is a bottom plan view of the lid in accordance with the second embodiment of the invention.
